UNITED STATES PATENT OFFICE.

EMMITT S. ANDERSON, OF FORT FRANCIS, ONTARIO, CANADA.

COUCH ROLL.

Application filed July 8, 1924. Serial No. 724,853.

To all whom it may concern:

Be it known that I, EMMITT S. ANDERSON, a citizen of the United States, residing at Fort Francis, in the Province of Ontario and Dominion of Canada, have invented 5 certain new and useful Improvements in a Couch Roll, of which the following is a specification.

This invention relates to couch rolls especially adapted to be used upon paper making machines and it consists in the novel features hereinafter described and claimed.

An object of the invention is to provide a couch roll which will eliminate the 15 necessity of compelling the use of the jacket laced about such rolls as is now the practice and which is objectionable owing to the fact that the lacing frequently becomes twisted, thus forming lumps and causing 20 damage to the machine and the products.

With this object in view the structure comprises a roll consisting of a body or core made of cast iron and having a plurality of spirally disposed ribs extending the full

25 length thereof. These ribs are provided with transversely disposed heads which are convexly curved thereby preventing the said head from having a tendency to develop corners or sharp angles while running.

30 A series of disks of pressed felt is threaded upon the ribs and the core and the said disks extend the full length of the core. Collars are mounted upon the end portions of the core at the ends of the series of disks.

35 Gudgeons are mounted upon the ends of the core and are disposed over the end portions of the shaft which passes centrally through the core.

In the accompanying drawings:

40 Figure 1 is a longitudinal sectional view of the couch roll,

Figure 2 is an enlarged fragmentary side elevation of an end portion of the couch roll.

45 Figure 3 is a transverse sectional view of the couch roll.

Figure 4 is an end elevation of one the gudgeons used upon the couch roll.

Figure 5 is a fragmentary side elevation of 50 one of the said gudgeons.

Figure 6 is a side elevation of one of the collars used upon the couch roll.

Figure 7 is an edge view of said collar.

Figure 8 is a side elevation of one of the 55 disks used upon the couch roll.

Figure 9 is an edge view of said disk.

The couch roll comprises a cylindrical core 1 having upon its outer periphery four spirally disposed spaced ribs 2, the said ribs being provided at their outer edges with 60 heads 3 which are convexed transversely. The ribs extend the full length of the core. The core is provided with a longitudinal central bore in which is located a shaft 3'. Disks 4 of compressed felt are threaded up 65 on the core 1 and the disks are provided with notches 5 which snugly receive the ribs and the head portions 3 thereof. Collars 6 are mounted upon the end portions of the core 70 and the said collars are disposed at the ends of the series of disks 4. The collars are provided with notches 7 which receive the end portions of the ribs and the outer corner portions of the collars are beveled as at 8. Gudgeons 9 are mounted upon the ends of 75 the shaft 13 and secured by means of nuts 10, and the said gudgeons are provided at their inner ends with disks 11 having notches 12 which receive the ends of the 80 ribs 2.

When the nuts are tightened upon the shaft the disks of the gudgeons force the collars in close contact with the terminal disks and the disks are compressed upon the ribs of the core, thus securely holding the disk and they may be trued up by grinding in order that their edge surfaces may lie in the same cylindrical plane.

After the disks 4 have been assembled 90 upon the shaft 3, the nuts 10 are turned up tight so that the disks will fit tightly against each other. This will give the roll a hard surface and the roll may then be soaked in hot water for a sufficient length of time to permit the water to be taken up by the disks whereby the said disks are shrunk upon the shaft and their peripheries may be trued up by grinding in a usual manner. When the roll is not in use, the disks should be kept in 95 a moist condition.

Having thus described the invention, what I claim is:

1. A couch roll comprising a core having a central bore, a shaft located in said bore, spirally disposed ribs provided upon the periphery of the core, said ribs having head portions which are convexed transversely, disks threaded upon the core and the ribs, 105 collars applied to the ends of the core and the rib, gudgeons receiving the ends of the shaft and having disks which receive the ends of the core and the ends of the ribs and 110

nuts screwed upon the shaft and engaging the gudgeons.

2. A couch roll comprising a core having upon its periphery a series of spaced spirally disposed ribs, the ribs being provided at their outer edges with head portions, disks of felt threaded upon the core and the ribs, shoulders mounted upon the end portions of the core and the ribs, gudgeons mounted upon the end portions of the shaft and having disks which receive the end portions of the core and the rib.

3. A couch roll comprising a core having upon its periphery a series of spaced spirally

disposed ribs, the ribs being provided at 15 their outer edges with head portions, disks of felt threaded upon the core and the ribs, shoulders mounted upon the end portions of the core and the ribs, gudgeons mounted upon the end portions of the shaft and having disks which receive the end portions of the core and the ribs, nuts screwed upon the shaft and engaging the gudgeons, the felt disks being shrunk by the application of moisture upon the core and the ribs. 25

In testimony whereof I affix my signature.

EMMITT S. ANDERSON.
